Inventor,
B. B. Christ
By his Attorney,
W. B. Hutchinson.

UNITED STATES PATENT OFFICE.

BERNHARD B. CHRIST, OF BROOKLYN, NEW YORK.

COUPLING FOR NECKLACES.

1,238,495.

Specification of Letters Patent. Patented Aug. 28, 1917.

Application filed February 20, 1917. Serial No. 149,773.

To all whom it may concern:

Be it known that I, BERNHARD B. CHRIST, a citizen of the United States, and a resident of the borough of Brooklyn, city of New York, county of Kings, and State of New York, have invented a new and useful Improvement in Couplings for Necklaces, of which the following is a full, clear, and exact description.

10 My invention relates to improvements in couplings for uniting the meeting ends of necklaces, bracelets, belts, and in fact any similar or analogous articles in which it is desirable to have the meeting members quickly and safely united and easily detachable or separable. It is customary to provide a spring snap which will fasten the meeting ends of such articles together, but often a single snap or catch of the kind generally used will become unfastened and the article will be lost, or else it will not quite catch when one thinks it is secure. The object of my invention is to provide in connection with a suitable main snap or catch, a safety snap or catch which will suitably secure the meeting ends of the article to which the coupling is applied, and to arrange the safety so that it will catch at a different point than the main catch and operate at a different time, and preferably to arrange it so that the tension of the safety catch will be at right angles to the tension of the main snap catch. Thus when the snap member is inserted in the socket member of the coupling, the safety snap or catch will first pass by its engaging shoulder, and if the main catch should not be pushed in far enough, the safety would hold so as to provide against accidents, and if the main catch is pushed into the socket member so as to make a firm engagement, it will serve its purpose, and when it is released either intentionally or accidentally, the snap member will only pull out part way because the safety will then engage its shoulder and the safety has to be released before the two members can be separated.

Another object of my invention is to produce a cheap structure which will be highly efficient as specified, and to arrange the operating parts so that they will work very smoothly and easily, opening with a light touch of the finger.

Reference is to be had to the accompanying drawings forming a part of this specification, in which similar reference char-

acters indicate corresponding parts in all the views.

Figure 1 is a plan view of a bracelet showing my coupling members applied thereto. 60

Fig. 2 is a plan of the socket member.

Fig. 3 is a plan of the plug or snap member.

Fig. 4 is a side elevation of the socket member. 65

Fig. 5 is a side elevation of the opposed members.

Fig. 6 is a longitudinal section of the socket member.

Fig. 7 is a longitudinal section of the 70 complete coupling with the two members in engagement,

Fig. 8 is an end view of the socket member.

Fig. 9 is an end view of the plug or snap 75 member.

Fig. 10 is a horizontal or sectional plan of the coupling with the two parts in engagement.

Fig. 11 is a view similar to Fig. 10 but 80 with the main snap released and the safety in engagement, and

Fig. 12 is a broken perspective partly in section bringing out clearly the construction of the safety and its corresponding shoulder. 85

The bracelet 10 may of course be a necklace, belt, or other flexible article, having end portions which it is desirable to connect and separate. At one end I show a socket member 11, and at the opposite end a plug 90 or snap member 12. It will be understood of course that the body of the article can be of any flexible nature, and that any materials suitable for the purpose can be used in constructing the coupling. 95

The socket member 11 is hollow, and is preferably though not necessarily of rectangular shape, and it has at its front end a horizontal slot 13 extending all the way across it, and located preferably near the bottom. This leaves an overhanging ledge or shoulder 14 at the front end which can engage the spring catch 15 when the latter is pushed inward behind the shoulder. This catch 15 comprises the main catch and is 105 similar to catches generally used for this purpose. It is in the form of a leaf spring, doubled over at its inner end and returned upon itself as shown at 16, the lower member extending outward beyond the end of the 110 socket member 11 and having an eye 17 or some means of connecting with the bracelet,

necklace, or whatever article it is used in connection with.

The catch or snap 15 has near its free edge a lug or finger piece 18 which projects upward through the slot 19, the latter being perpendicular to the slot 13 so that by pressing downward on the lug 18 the snap can be released and the plug member pulled out. So far as described the structure is 10 not dissimilar from any forms of snap catches. At one end of the plug member is a spring arm 20 which lies generally parallel with the plug member and with the snap 15, though the tension of the spring arm is 15 lateral with reference to the plug member as shown in the drawings, and the plug member is cut away opposite the spring arm as shown best in Fig. 10 to permit the spring arm to be pushed inward when desired.

20 The spring arm 20 has a shoulder or ledge 21 thereon which it will be observed is well behind the free end of the snap 15, and this is adapted to engage the shoulder 22 (see Fig. 12) which is arranged at the front end 25 of the socket member 11, and projects downward below that part of the front end 14 which engages the snap 15, this shoulder 22 in fact being very narrow and near one edge of the socket member 11. This member 20 and shoulder 21 comprise the safety or safety snap, and it has at its free end a finger piece 23 which projects slightly forward from a slot 13, and is adapted to slide laterally in the said slot under the tension of the spring 35 of the arm 20, so that when the shoulder 21 is behind the shoulder 22, the member 23 will project slightly to one side and a little forward of the socket member 11. It is not necessary, however, that the member 23 40 project both to one side and forward of the member 11, as if it projects in either direction it can be touched by the finger so as to release the safety snap, that is so as to push the shoulder 21 inward to enable it to pass 45 the shoulder 22 when the plug member is pulled from the socket member.

It will be noticed that when the plug member is inserted in the socket member, the safety catch or shoulder 21 will pass behind 50 the shoulder 22 before the snap 15 passes behind the shoulder 14, and in case the plug member is carelessly pushed in only part way, the safety will still hold. To properly secure the coupling, however, the plug member should be pushed in until the snap 15 55 engages behind the shoulder 14. When the members are to be separated, one simply pushes downward on the lug 18, thus freeing the snap 15 from its shoulder, and at the 60 same time pushes the plug member outward; after a little movement the shoulder 21 engages the shoulder 22, and this is freed by pushing the finger piece 23 inward laterally so as to free the shoulder 21 from the shoulder 22.

In practice the springs are made light and the device can be very easily operated. It will be understood that the coupling can be made in very many designs and shapes, and of many different kinds of material, without affecting the nature of the invention. 70

I claim:

1. A coupling of the kind described comprising a socket member and a plug entering the socket member, a main snap catch on the 75 plug to engage the socket member, a safety catch on the plug independently engaging the socket member, and independent means for releasing each catch.

2. A coupling comprising a socket member 80 and a plug member entering the socket member, a main snap catch on the plug engaging a corresponding part of the socket member, and a safety catch on the plug working at an angle to the main catch and 85 also engaging the socket member.

3. A coupling comprising a socket member 90 and a plug member engaging the socket member, a main snap catch on the plug engaging a corresponding part of the socket 95 member, a safety catch on the plug also engaging a part of the socket member but at a different time from the main catch when the plug is moved in the socket member.

4. A coupling comprising a socket member 95 and a plug member entering the socket member, a main snap catch carried by the plug and engaging the socket member, and a safety catch also carried by the plug and arranged behind the main catch and engaging 100 a corresponding part of the socket member.

5. A coupling comprising a socket member 105 and a plug member entering the socket member, the plug member having a main snap catch engaging the socket member, and a safety catch moving at an angle to the main catch and arranged out of alignment with the main catch, the safety catch serving to also engage the socket member and having means 110 for releasing it independent of the main snap.

6. A coupling comprising a socket member having two shoulders, and a plug member 115 entering the socket member, said plug member having a main snap catch to engage one shoulder of the socket member, and an independent safety catch to engage the second shoulder of the socket member.

7. A coupling comprising a socket member slotted in one end and provided with shoulders adjacent the slot, one shoulder being at a different elevation than the other, and a plug member entering the slot of the socket member, said plug member having a main snap catch to engage one shoulder of the 125 socket member, and an independent safety snap catch to engage the second shoulder of the socket member.

8. A coupling comprising a slotted socket member, and a plug member entering the slot 130

- of the socket member, said plug member having a main snap catch to engage a corresponding part of the socket member, and a safety catch lying generally parallel with the main catch but with a tension essentially at right angles to that of the main catch, said safety catch engaging a corresponding part of the socket member and engaging at a different time from the main snap catch.
- 10 9. A coupling comprising a socket member slotted at one end and provided with shoulders, and a plug member entering the slot of the socket member, said plug member having a main catch in the form of a leaf-spring engaging the main shoulder of the
- 15

socket member, and a safety catch also in the form of a leaf-spring but with its tension at right angles to that of the main catch, the safety catch engaging the second shoulder of the socket member.

20

10. A coupling of the kind described comprising a socket member and a plug entering the socket member, said plug having a plurality of snap catches thereon to successively engage corresponding parts in the socket member.

BERNHARD B. CHRIST.
